UNITED STATES PATENT OFFICE.

LEONARD B. BUCHANAN, OF WOBURN, MASSACHUSETTS.

ELECTRIC FUSE OR CUT-OUT.

No. 853,296.

Specification of Letters Patent.

Patented May 14, 1907.

Application filed August 22, 1904. Serial No. 221,629.

To all whom it may concern:

Be it known that I, LEONARD B. BUCHANAN, of Woburn, county of Middlesex, State of Massachusetts, have invented an Improvement in Electric Fuses or Cut-Outs, of which the following description, in connection with the accompanying drawings, is a specification, like characters on the drawings representing like parts.

This invention relates to electric fuses or cut-outs, and particularly to that type of inclosed fuses which are adapted, when the fuse wire is fused, to indicate the disrupted condition of the fuse wire, and the invention has for its object to provide a fuse of this class with means which will not only visually indicate the disrupted condition of the fuse wire, but which will also enable the disrupted condition of the fuse wire to be ascertained by simply feeling of the casing. This object is accomplished, in a general way, by providing a spring acting finger, which is held under tension by the fuse wire and which will move beyond the surface of the casing when the fuse wire is disrupted.

Figure 1 shows in side elevation an inclosed fuse or cut-out embodying this invention. Fig. 2 is a central longitudinal section of the fuse shown in Fig. 1. Fig. 3 is an enlarged section of the fuse taken on the line 3—3 of Fig. 1. Fig. 4 is a similar view showing the parts in a different position. Fig. 5 shows, in elevation, and partly in central longitudinal section, a modified form of my invention, Fig. 6 is a section of the fuse taken on the line 6—6 of Fig. 5, and, Fig. 7 is another modified form of my invention to be referred to.

Referring to Figs. 1 to 4, *a*, indicates the usual cylindrical shell or casing having caps *a'* on each end thereof. The shell or casing *a* is of suitable insulating material, and the caps *a'* are of metal, preferably copper, and constitute the terminals of the fuse. A fuse wire *b* is centrally arranged in the casing and embedded in a non-conducting filling, such as magnesia, or gypsum, and the ends of said wire are soldered to the terminal caps *a'*. A shunt fuse wire *e* is also provided in the casing and is arranged adjacent the casing walls with its ends attached to the caps *a'*. A normally straight or nearly straight indicating spring acting finger *d* is secured at one end to the casing, as for instance; the inner end of one of the caps *a'*, is notched, as shown at *a²*, to provide a recess in which said finger may be located, and one end of the finger is passed

beneath the cap, at the end of said recess and held by said cap against the casing. A loop *f* of wire is secured to the opposite or free end of said finger. Before both ends of the shunt *e* are connected to the caps the spring acting finger *d* is pressed down, being bent about the casing, so that it lies nearly flush with the end of the cap, and the loop *f* thereon is passed through a small aperture *a³* in the casing, and the shunt wire *e* is passed through the end of said loop within the casing. The shunt wire *e* thus holds the finger down against the casing and when in this position said finger closes the aperture *a³*, as shown in Fig. 3, and as said finger, when in this position, nearly fills the notch *a²*, the presence of said finger is scarcely noticeable. When the shunt wire *e* is disrupted it will no longer hold down the finger in the position shown in Fig. 3, but said spring will be released and will straighten out and assume the position shown in Fig. 4, thus indicating the disrupted condition of the fuse wire.

In Figs. 5 and 6, the shunt fuse wire *e* is omitted, and the loop on the end of the indicating finger is made longer being represented at *j'* and the fuse wire *b* is passed therethrough and acts to hold down the indicating finger against the casing in the manner before described. The operation in this instance is, obviously, the same as that already described. The movement of the spring to the position shown in Fig. 4, not only makes it perfectly apparent to the eye that the fuse wire has been disrupted, but if the device was situated where it could not be seen, or could only be felt with the hand, the condition of the fuse wire could nevertheless be readily ascertained.

Referring to Fig. 7, the shunt wire *e* extends out through the aperture *a³* and may have a loop at its extremity, and the indicating finger will be attached at one end to the casing and electrically connected with one of the terminal caps, and at the other end will extend through the loop, or will be otherwise connected to said shunt wire *e*. In this instance but one end of the shunt wire will be connected with the terminal.

Having described my invention what I claim as new and desire to secure by Letters Patent is;

1. In an inclosed fuse or cut-out, a cylindrical casing having an aperture through the side thereof, a pair of terminal caps closing the ends of said casing, one of said caps hav-

ing a notch in its edge, a fuse wire connected at its ends to said caps, an indicating spring having one end held between said casing and the notched cap, and a holding wire connected to the other end of said spring which passes through said aperture and encircles said fuse wire and acts to hold said spring under tension in said notch, substantially as described.

10 2. In an inclosed fuse, a casing having end caps, one of which is notched, a fuse-wire contained in said casing, a spring actuated

indicator on the outside of the casing which is contained in the notch of the end cap, and means extending through a hole in the casing for connecting said indicator with the fuse-wire, substantially as described.

In testimony whereof, I have signed my name to this specification, in the presence of two subscribing witnesses.

LEONARD B. BUCHANAN.
